SYRINGE

Hans Herbert Schulz, London, England

Application February 6, 1936, Serial No. 62,575
In Great Britain April 27, 1935

15 Claims. (Cl. 128—237)

This invention relates to syringes especially suitable for use for surgical and medical purposes of the kind in which the filling tube also acts as the discharge tube, and is an improvement on the invention forming the subject matter of my copending application Serial No. 54,811, filed December 17, 1935, for Letters Patent according to which during the filling operation liquid is forced into an expansible and contractible storage chamber in the form of a rubber sleeve normally lying in close proximity with the outer wall of the apparatus, whence it is discharged at a regulatable rate through a valve.

Amongst the desiderata for apparatus of this class are the following. They should be light and portable, simple in action and easy to manipulate with a single hand, the discharge should take place at a constant rate, and without the need of manual force, and the assemblage, dis-

20 assemblage and cleaning operations should be simple. Further they should be simple and cheap to construct, the separate parts should be few, and the apparatus should so far as possible be capable of manufacture from hygienic and easily 25 sterilizable materials. The avoidance of any tendency to leakage is also of considerable importance.

The present invention is intended to fulfil these requirements and according to it the 30 tractible storage chamber is made in the form of a bag or sac which completely encloses one end of the apparatus and normally lies in close proximity with the cylindrical walls or a portion thereof, and the end of the bag is secured to the cylinder wall in a fluid tight manner. The 35 valve is situated at the end of the apparatus preferably remote from the nozzle and enclosed by the said bag or sac, and is operable by pressure through the same, and the valve may be 40 retained in its seat by the elastic reaction thereof. In the preferred form the valve is made integral with the bag or sac.

According to another feature of the invention the apparatus may be filled by resting the nozzle 45 on the bottom of a basin or the like and then pulsating. Other features will become apparent from the description hereunder.

Examples of the invention will now be more particularly described by reference to the accompanying drawings.

Fig. 1 is a longitudinal section of one form.

Fig. 2 is a similar view of another form.

Fig. 3 is a sectional detail of a modification.

Fig. 4 is a sectional detail of a modification.

Fig. 5 is a part sectional view of a further modification.

Fig. 6 is a part sectional view of a still further modification, and

Fig. 7 is a sectional view showing an attachment for filling from a tap.

In Fig. 1 an india rubber bag 1 is adapted to be slipped or drawn over to hood an open ended pump barrel 2 having an internal screw-thread 2a at that end adjacent to the end wall 3 of the bag 1. Apertures 4 in the wall of the barrel communicate with apertures 5 in the tapering wall of a plug seating ring 7, the conical centre of which makes a fluid tight joint with the wall of a tapering central aperture in an internal flange 9 of the barrel 2. The cylindrical flange 1a of the ring 7 fits snugly in a flanged external screw threaded ring 10 on to which the corresponding end of the barrel 2 is screwed.

The edges of the flange 10a of the ring 10 may be knurled to interlock with the elastic wall of the bag 1. The external portion 1a of the bag 1 may be knurled for facilitating hand gripping in assemblage and disassembly. The bag 1 may be secured to the ring 10 in any convenient way, as by moulding the rubber through anchoring slots 10b of the flanged portion 10a thereof. An inner flange 1b formed on the bag 1 may be sprung over the flanged portion 10a of the ring 10 so as to lie between it and the end of the barrel 2 whereby the bag 1 is securely retained in position.

The seating ring 7 which has a push fit with the ring 10, is fast with a hollow stem 11 which extends axially along the barrel 2. The outer end of this stem 11 forms a seating 12 for a valve 13 whose spindle 14 passes through the stem 11 and is secured by moulding by an anchoring plate 15 to the end wall 3 of the bag. The thickened portion 3a of the end wall is 40 pressed by the finger or thumb to move the valve 13 axially off its seating.

Thus the interior of the barrel 2 is divided into charging and discharging chambers 16 and 17 of which the latter communicates through apertures 4 and 5 with the space formed between the outside of the barrel 2 and the inside of the bag 1 when the latter is expanded and the former receives a piston 19.

The end of the outer wall of the barrel 2 remote from the bag end 3 has a threaded collar 2b and, spaced therefrom is another collar 2c so as to form an annular channel in which a beaded free edge 1c of the bag 1 is sprung. The threaded collar 2b is engaged with a hollow,

medially apertured, conical nut 20 which, when 5 screwed home, compresses the beaded edge 1c of the bag 1 against a radial abutment wall of the other collar 2c and produces an effective fluid tight closure of the bag 1 around the barrel 2 and at the only joint which the bag 1 requires.

The collar 2c may be chamfered back away from its abutment wall and the bag 1 similarly shaped by expanding it near its open end.

10 The piston 19 has a suction flap valve 21 and an outer tubular extension 22. The hollow stem 11 passes through the piston 19 and intrudes into the tube 24 when this is the nozzle tube, or into one part of the telescopic tubes 23 and 24.

15 The tube 23 may be a catheter part which can be drawn out of the other part and retained in an inclined position with respect thereto and to the axis of the instrument by an inclined screw-threaded connection 24b, 24a. An overhang may 20 be provided between the two tubes to prevent disconnection.

A non-return valve 25, controls inlet ports 26 into the elastic storage chamber formed between 1 and 2, so that on relative movement occurring 25 between the barrel 2 and the piston 19, so that on pulsating or reciprocating the cylinder whilst the nozzle 23a is pressed against the bottom of a vessel of liquid, a charge of liquid is pumped into the elastic storage chamber.

30 The piston 19 is returned by an elastic sleeve 27 anchored at one end to the piston head, and at the other end by a beaded edge 27a engaging over a shoulder 33 of the barrel, and clamped by an internal radial wall 20a of the conical nut 20 against the corresponding end of the barrel.

To assemble the appliance the sac 1 is secured to the ring 10. The plug 7, 7a is then fitted in position as shown with the stem 11 surrounding the spindle 14 and the valve 13 is screwed onto the spindle.

40 The barrel 2 is screwed on to the ring 10 and the bag when in its normal position has its free edge sprung over the abutment collar 2c, the piston 19 is then inserted into the barrel 2 and the free edge of its elastic sleeve is folded over the corresponding end of the barrel 2, whereafter, the telescopic members having been assembled together, the apertured conical nut 20, is passed thereover and screwed onto the barrel.

50 In Fig. 2, the pump barrel 30 is provided with a screw threaded flange 32. A flanged valve body 33 is provided with a shouldered down screw threaded portion 33a to screw into such screw threaded flange 32.

55 The part 33a is provided with a seating with which a discharging valve 34 co-operates. The barrel 30 is thus divided so as to form an end chamber which is in communication through apertures 35 and 36 with the storage space between the external wall of the barrel 30 and the sac or bag 37, the remaining part 38 of the cylinder receiving the piston 39.

The end wall of the sac 37 has a thickened integral central button-like part 40, a stem 41 extending axially inwards from such button like part 40, having the conical discharging valve 34. The end wall of the sac or bag (1 or 37) is so arranged that the button lies flush with or below the plane of the corresponding end of the sac or bag so as to lessen the risk of the discharge valve being opened inadvertently while the device is being handled.

In Fig. 2 the piston is in the form of an open-ended cylinder 39 which surrounds the cylindrical wall of an elastic sleeve 42 having a thick-

ened inner part 43 medially perforated with which the correspondingly formed inner end of the catheter 44 can make a fluid tight joint when the tubes 44 and 45 are telescoped and the device is housed in a suitable two-part container 46 adapted to be screwed together to hold the catheter 44 against the part 43.

Secure connection of the piston 39 with the rubber sleeve may be effected by moulding the thickened end thereof to a radial internal flange 10 39a of the piston wall by anchoring slots 39b.

The suction valve 47 is an expanding rubber plug in the nozzle 48 and having a central way 47a and circumferential ways formed by spaces 47b between the tapered wall of the plug and the 15 tapered end of the nozzle leading to openings 49 in the nozzle 48 communicating with a central bore 50a. When pressure is exerted against the head of the plug by pressing this against the bottom of a vessel the way 47a is sealed and 20 the spaces 47b sealed up by distortion of the plug. The non-return valve is indicated by 48a.

On relative movement occurring between the cylinder and the piston realized by pulsating or reciprocating the cylinder whilst the nozzle or 25 catheter is pressed against the bottom of a vessel of liquid, the suction valve 47 closes during the stroke which pumps liquid into the elastic storage chamber and opens when the pressure of the nozzle against the bottom of the vessel of liquid 30 is released during the suction stroke.

By turning the sac 37 inside out it is easy to assemble the discharge valve body over the discharge valve and to spring the internal flange 40a of the sac over the flange of the valve body 33. 35 The cylindrical wall of the sac 37 is then folded back to its normal position and the barrel 30 slidden therein and engaged with the discharge valve body 33. The open end of the sac is then sprung over the locking shoulder on the barrel, 40 and the piston 39 is inserted into the barrel and the bead or flange of its rubber sleeve 42 sprung over its locking shoulder on the cylinder. The telescopic members having been assembled together the apertured conical nut 53 is passed 45 thereover and screwed on to the barrel.

The two part container 46 for housing the device may be so proportioned and arranged that the container parts may be screwed together sufficiently to seal off the nozzle 48 by closing the 50 plug suction valve 47 and sealing the medial perforation 47a therein as well as sealing off the inner end of the catheter 44.

The appliances can be as readily disassembled when desired.

Fig. 3 shows a modification in which the elastic sleeve 42 and its head 43 is anchored by anchoring slots to a differentially threaded ring 55 screwed externally to the tube 45 and internally to the piston 39. Such an arrangement allows of easy 60 disconnection of the parts for cleaning or renewal.

Fig. 4 shows a modification in which the suction valve is situated in the nozzle or telescopic member 23 and in which provision is made for the insertion of interchangeable single channel nozzles 56.

Fig. 5 shows a modification in which the piston 65 60 has a screw union 61 with the tube 45.

According to the construction shown by Fig. 6, the cylinder 70 has a closed end 71 in which the discharge valve 72 is seated. 73 is the sac and 74 the non-return valve.

Fig. 7 shows a construction adapted to be filled 75

from a water-tap 101 by removal of a discharge nozzle and fitting a connector 100.

In all cases the pump filling means including the suction valve may be omitted where it is desired to rely only upon tap filling.

The syringe can be constructed almost entirely of a phenolic condensation product, or like substance, and rubber, so as to be of very light weight and readily cleaned, disinfected and dried.

10 Apparatus according to the present invention is well suited for manufacturing by moulding processes.

What I claim is:—

15 1. A syringe or the like of the kind hereinbefore referred to, comprising an inner rigid tubular member, an outer elastic sac or bag surrounding said rigid tubular member and completely enclosing one end thereof, the end of such sac being secured to such tubular member in a fluid tight manner and the said member being constructed so as to form between its external surface and the sac a fluid-storing space, the walls of the sac normally lying in close proximity to the external surface of the tubular member 20 and being adapted to be expanded and elastically energized by fluid pressure, a fluid inlet from the interior of said tubular member to said storage space and a one-way valve controlling said inlet whereby to permit fluid to enter into said storage 25 space and elastically energize the walls of said sac, an outlet from said storage space and a regulatable push discharge valve cooperating with said outlet, said valve being situated inside the sac and being operable by pressure on the sac 30 so that the fluid can be automatically discharged from the storage space by the pressure exercised by the elastically energized walls of the sac.

2. A syringe or the like of the kind hereinbefore referred to, comprising an inner rigid tubular member, an outer elastic sac or bag fitted over said rigid tubular member so as to surround said member and completely enclose one end thereof, the side walls of such sac being secured at each end to such tubular member in a fluid tight manner and the said member being constructed so as to form between its external surface and the sac a fluid-storing space, the walls of the sac normally lying in close proximity to the external surface of the tubular member and being adapted to be expanded and elastically energized by fluid pressure, a fluid inlet from the interior of said tubular member to said storage space and a one way valve controlling said inlet whereby to permit fluid to enter into said storage space and elastically energize the walls of said sac, an outlet from said storage space and a regulatable push discharge valve cooperating with said outlet, said valve being situated inside the sac and being operable by pressure on the sac so that the fluid can be automatically discharged from the storage space by the pressure exercised by the elastically energized walls of the sac, the end wall of the sac being adapted to be elastically energized when the discharge valve 55 is operated and serving elastically to force the valve to close said outlet when the operating pressure is removed.

3. A syringe or the like of the kind hereinbefore referred to, comprising an inner rigid tubular member, an outer elastic sac or bag fitted over said rigid tubular member so as to surround said member and completely enclose one end thereof, the end of such sac being secured to such tubular member in a fluid tight manner and the said member being constructed so as to form be-

tween its external surface and the sac a fluid-storing space, the walls of the sac normally lying in close proximity to the external surface of the tubular member and being adapted to be expanded and elastically energized by fluid pressure, a fluid inlet from the interior of said tubular member to said storage space and a one way valve controlling said inlet whereby to permit fluid to enter into said storage space and elastically energize the walls of said sac, an outlet from said storage space formed in that end wall of such tubular member which is adjacent the end wall of the sac and a regulatable push discharge valve cooperating with said outlet, said valve being formed integrally in one piece with the end wall 10 of the sac and projecting inwardly from the inner face of said wall, said valve being operable by pressure on the end wall of the sac so that the fluid can be automatically discharged from the storage space by the pressure exercised by 15 the elastically energized walls of the sac.

4. A syringe or the like as claimed in claim 1, in which the side walls of the sac are attached in a fluid tight manner to each end of said inner tubular member.

5. A syringe or the like as claimed in claim 1, in which the push valve control is countersunk in the normal condition of the syringe within the tubular member so as to prevent accidental operation.

6. A syringe or the like of the kind hereinbefore referred to comprising an inner rigid tubular member serving as a pump cylinder, an outer elastic sac or bag fitted over said inner rigid tubular member so as to completely enclose one 35 end thereof, the end of such sac or bag being secured to such tubular member in a fluid tight manner so as to form a contractible storage space between the walls of the sac or bag and the said member, the said walls of the bag normally lying in close proximity to the tubular member, a one-way valve controlled inlet to said storage space for filling, a hollow stem extending axially along the cylinder and carried by said tubular member, a pump piston movable along said 40 stem, and a regulatable push discharge valve situated inside the sac and having its seating at the outer end of said stem, a spindle connecting said push discharge valve to the end wall of the sac, said discharge valve being operable by pressure 45 on the sac, so that the fluid is automatically discharged at a regulatable rate by reason of the elastic contraction of the said storage space.

7. A syringe or the like of the kind hereinbefore referred to comprising an inner rigid cylinder or barrel, an outer elastic sac or bag fitted over said inner rigid tubular member so as to completely enclose one end thereof, the end of such sac or bag being secured to such tubular member in a fluid tight manner so as to form a 60 contractible storage space between the walls of the sac or bag and the said member, the said walls of the bag normally lying in close proximity to the tubular member, a piston in said cylinder, a suction valve in said piston, a one-way valve 65 controlled inlet to said storage space, a hollow stem extending axially along said cylinder, so as to divide the cylinder into charging and discharging chambers, and a regulatable push discharge valve situated inside the sac and seated 70 at the outer end of said stem, and operable by pressure on the sac, so that the fluid is automatically discharged at a regulatable rate by reason of the elastic contraction of the said storage space.

8. A syringe or the like of the kind hereinbefore referred to comprising an inner rigid tubular member, a filling and discharging tube communicating with the interior of said member, an outer elastic sac or bag fitted over said inner rigid tubular member so as to completely enclose one end thereof, the end of such sac or bag being secured to such tubular member in a fluid tight manner so as to form a contractible storage space between the walls of the sac or bag and the said member, the said walls of the bag normally lying in close proximity to the tubular member, a one-way valve controlled inlet to said storage space for filling from the interior of the tubular member and expanding the walls of the sac, and a discharge outlet from said storage space and a regulatable push discharge valve situated inside the sac and cooperating with said outlet, said discharge valve being operable by pressure on the sac, so as to permit the stored fluid to be automatically discharged at a regulatable rate by reason of the elastic contraction of the said storage space.

9. A syringe or the like of the kind hereinbefore referred to comprising an inner rigid tubular member serving as a pump cylinder, a filling and discharging tube, and a piston connected thereto and working in said cylinder, an outer elastic sac or bag fitted over said inner rigid tubular member so as to completely enclose one end thereof, the end of such sac or bag being secured to such tubular member in a fluid tight manner so as to form a contractible storage space between the walls of the sac or bag and the said member, the said walls of the bag normally lying in close proximity to the tubular member, a one-way valve controlled inlet to said storage space for filling by causing relative movement between the piston and the cylinder, a valve adapted to be closed by the pressure exerted by the tube against the bottom of the vessel from which the fluid is being pumped into the expansible storage chamber and automatically opened during the suction stroke, and a discharge outlet from said storage space and a regulatable push discharge valve situated inside the sac and cooperating with said outlet, said discharge valve being operable by pressure on the sac, so as to permit the fluid to be automatically discharged at a regulatable rate by reason of the elastic contraction of the said storage space.

10. A syringe or the like of the kind hereinbefore referred to, comprising an inner rigid hollow cylinder or barrel having an end wall, an outer elastic sac or bag fitted over said inner rigid tubular member so that its end wall lies adjacent to said end wall of the rigid cylinder, the free end of such sac being secured to such cylinder in a fluid tight manner so as to form a contractible storage space between the walls of the sac and the said cylinder, the said walls of the sac normally lying in close proximity to the cylinder, a discharge opening in said end wall of the cylinder and a regulatable push discharge valve situated inside the sac and seated in said opening, said valve being operable by pressure on the sac so as to permit the fluid to be automatically discharged at a regulatable rate by reason of the elastic contraction of the said storage space.

11. A syringe or the like of the kind hereinbefore referred to, comprising an inner rigid tubular member serving as a pump cylinder, a filling and discharging tube and a piston carried by said tube and arranged to work in said cylinder

- walls of the bag normally lying in close proximity to the tubular member, an outlet from said space and a regulatable push discharge valve situated inside the sac and cooperating with said outlet, 5 said valve being integral with said sac and operable by pressure on the sac, so as to permit the fluid to be automatically discharged at a regulatable rate by reason of the elastic contraction of the said storage space.
- 10 15. A syringe or the like of the kind hereinbefore referred to comprising an inner rigid cylinder or barrel, an open ended piston working therein, a filling tube serving also as a discharge tube, a removable nozzle at the end of said tube, 15 an outer elastic sac or bag fitted over said inner
- rigid tubular member so as to completely enclose one end thereof, the end of such sac or bag being secured to such tubular member in a fluid tight manner so as to form a contractible storage space between the walls of the sac or bag and the said member, the said walls of the bag normally lying in close proximity to the tubular member, a discharge outlet from said space and a regulatable push discharge valve situated inside the sac and cooperating with said outlet, said valve being 10 operable by pressure on the sac so as to permit the fluid to be automatically discharged at a regulatable rate by reason of the elastic contraction of the said storage space.

HANS HERBERT SCHULZ. 15
